UNITED STATES PATENT OFFICE.

WALTER GREEN, OF MONTREAL, QUEBEC, CANADA.

GANGWAY.

1,144,836.

Specification of Letters Patent. Patented June 29, 1915.

Application filed June 20, 1914. Serial No. 846,293.

To all whom it may concern:

Be it known that I, WALTER GREEN, a subject of the King of Great Britain, and resident of the city of Montreal, in the 5 Province of Quebec and Dominion of Canada, have invented new and useful Improvements in Gangways, of which the following is a full, clear, and exact description.

This invention relates to improvements in 10 gangways or loading platforms, and the object is to provide a gangway which may be used to bridge the gap between two cars or between the car and platform during loading.

15 A further object is to provide a gangway which will be held against longitudinal movement or creeping which frequently results in serious accidents.

A still further object is to provide on a 20 gangway holding means which may be adjusted to any variation of the space to be bridged.

To accomplish the above outlined objects, a gangway is provided consisting of the 25 usual platform reduced in thickness at the ends, and metal shod to resist wear. On the underside of the platform, guides are provided containing slidable members which may be adjusted in the guides to make up 30 with the guides the space to be bridged.

In the drawings which illustrate the invention:—Figure 1 is a side elevation of the device in position between two cars. Fig. 2 is a plan view of same. Fig. 3 is an enlarged cross section on the line $\alpha-\alpha$, Fig. 2. Fig. 4 is an enlarged side elevation partly in section. Fig. 5 is a view similar to Fig. 1 showing the gangway connecting two cars of unequal height.

40 Referring more particularly to the drawings, 6 and 7 designate the floors of two cars or of a car and platform or the like, which are spaced apart by a gap, designated 8.

The gangway consists of a platform 9 reduced in thickness at the ends and provided 45 with metal shoes 10 in the usual manner. On the underside of the gangway, a pair of longitudinally disposed guide channels 11 are secured having one end closed by a member 12. The flanges of these guides are provided with inwardly projecting ribs 13 which hold the longitudinal slidable members 14 against escape from the guides. Near the open ends of the guides, the lower 50 rib 13 is provided with a plurality of regularly spaced notches 15, in which a plurality

of pins 16 carried by the slides 14 are engageable. These pins 16 are mounted toward the free ends of the slides 14, and in order that the slides may be lifted to disengage the pins from the notches, the slides are slightly tapered from their inner to their outer ends, as shown by the space 17. For convenience of operation, each slide is provided with a handle 18. The outer end of each slide is provided with a protective shoe 19 secured to the upper edge thereof and bent down over the end and projecting a short distance below the lower edge, as clearly shown in the drawings. These shoes 70 protect the ends of the slides from wear, and in addition, the downwardly projecting portion 20 increases the bearing surface, so that when the gangway is used to connect objects of different heights, the inclination or oscillation of the gangway as the load runs off 75 will not have the effect of disengaging the slide.

The operation of the device is very simple. The gangway is placed across the gap between the two objects 6 and 7, and the closed ends of the guides 11 brought into abutting relation with one of said objects. The slides are lifted in the guides to disengage the pins 16 from the notches 15 and are then adjusted 80 in the guides until the shod ends of the slides engage the other object, as clearly shown in Figs. 1 and 5. When the slides are released, they drop by gravity and the engagement of the pins 16 in the notches will 85 hold the slides against longitudinal movement, so that the gangway will not creep.

The gangway may be put to use or removed instantly, and is not in any way attached to either object.

Having thus described my invention, what I claim is:—

1. In a gangway, the combination with a platform of a pair of longitudinal guide members secured to the lower side of said 100 platform, slides movably mounted in said guides, locking means connecting the slides and guides, abutment faces of increased depth on the outer ends of the slides, said slides being tapered from the inner to the 105 outer ends to permit vertical unlocking movement.

2. In a device of the character described, a platform, a pair of channel shaped guides secured to the lower side thereof, inwardly 110 projecting ribs on the flanges of said guides, the lower of said ribs having a plurality of

notches toward one end thereof, abutment members closing the engaged ends of said guides, slidable abutment members mounted in said guides and retained by the ribs thereof, said members being tapered from the closed end of the guides toward the open ends, an abutment shoe of increased depth secured to the free end of each of said slid-
5 able members, and pins on said members

engageable with the rib notches to hold the 10 members against movement in the guides.

In witness whereof, I have hereunto set my hand in the presence of two witnesses.

WALTER GREEN.
